UNITED STATES PATENT OFFICE

GEORGE JAKOPEC, JOHN F. SALLEY, AND VINCENT SCHWARZ, OF CHICAGO, ILLINOIS

BURGLAR ALARM

Application filed August 8, 1929. Serial No. 384,306.

This invention relates to certain new and useful improvements in burglar alarms.

The primary object of the invention is to provide a burglar alarm especially designed and constructed for association with a door for sounding alarms, both visual and audible upon opening movement of the door, the devices being manually controlled for rendering them either operative or inoperative.

10 A further object of the invention is to provide a burglar alarm of the above type wherein the devices rendering the alarm mechanism operative and inoperative are shiftable from both the inner and outer sides of the door, the devices being manually operable from the inner side of the door and key operated at the outer side of the door.

With the above and other objects in view that will become apparent as the nature of 20 the invention is better understood, the same consists in the novel form, combination and arrangement of parts hereinafter more fully described, shown in the accompanying drawings and claimed.

25 In the drawings:—

Figure 1 is a fragmentary front elevational view of the wall structure and door equipped with the improved burglar alarm and illustrating the wiring diagram for one of the 30 audible and the visual signals;

Figure 2 is a side elevational view of the burglar alarm mechanism with the door and wall structure shown in section with the manually operated trip arm of the operating mechanism forwardly projected at the inner side of the door into operative position and illustrated by dotted lines in its retracted inoperative position;

40 Figure 3 is a side elevational view, partly in section, similar to Figure 2 showing the trip lever arms of the operating mechanism forwardly projected by key mechanism operated at the other side of the door as shown by 45 dotted lines in its inoperative position;

Figure 4 is an enlarged fragmentary front elevational view showing the operating mechanism for the burglar alarm in its forwardly projected operative position and further illustrating by dotted lines an inter-

mediate position of the mechanism between its operative and inoperative position;

Figure 5 is a vertical longitudinal sectional view taken on line 5—5 of Figure 4, showing the manually operable trip lever in its forwardly projected set position beneath the trip arm of the alarm device;

Figure 6 is a vertical cross-sectional view taken on line 6—6 of Figure 4 showing the movement resistance element for the latch 60 arm of the alarm device;

Figure 7 is a detail sectional view taken on line 7—7 of Figure 6 showing the guide arms for the conduit chamber of one of the audible signals members; and

Figure 8 is a vertical longitudinal sectional view taken on line 8—8 of Figure 7.

Referring more in detail to the accompanying drawings, and particularly to Figure 1, the reference numeral 10 designates a door 70 while the numeral 11 indicates a wall structure with which the door is associated, the door 10 being provided with the usual door locking mechanism 12 for locking the door in closed position. The burglar alarm includes audible signals 13 and 14 and a visual signal 15, the signals 13 to 15 being rendered operable by the mechanism 16 mounted on the door 10 and cooperating with the audible signal 13.

The audible signal 13 is adapted to fire a blank cartridge when set for such action upon unauthorized opening of the door 10 by the mechanism 16 cooperating therewith, the audible signal 13 comprising a tubular casing 17, base flanges 18 anchored to the wall 11 and housing a coil spring 19 for projecting the firing pin 20 from one end thereof, the firing pin being retracted to set position by the handle 21 upon its other end. The firing pin 20 is retained in its retracted set or firing position by the lever 22 pivotally mounted up on the pin 23 at the upper forward end of the casing 17 with a finger extension 24 adjacent the pivot pin 23 to be received in a side notch 25 in the firing pin 20 as shown in Figure 5, the free end of the lever 22 being limited in its movement toward the wall 11 by the angularly directed arm 26 carried thereby and engaging the wall as il-

lustrated, the free end of the lever 22 being disposed adjacent the free swinging edge of the door 10. The cartridge barrel 27 associated with the casing 17 and firing pin 20 has the base flange 28 thereof anchored to the wall 11 and spaced from the base flange 18 of the casing 17, the adjacent end of the casing 17 and barrel 27 being spaced apart a sufficient distance to permit the positioning 5 of a blank cartridge 29 as shown in Figure 8 between the casing and barrel for insertion in the barrel, but preventing the placing of a bullet carrying cartridge into the barrel. Different gauge or caliber cartridges may be 10 inserted in the barrel 27 by mounting therein the collar 30 shown in Figure 8. It is possible for the firing pin to be projected without firing the cartridge 29 and to accomplish this purpose; there is provided a 15 guard arm 31 pivotally mounted and tensioned on the pin 32 carried by the inner upper end of the barrel 27 to be swung into the path of movement of the firing pin 20 and covering the head of the cartridge 29, one 20 side of the swinging end of the guard arm 31 having an arcuate flange 33 to engage the rim 29a of the cartridge for limiting swinging movement of the arm and centering the same directly in line with the cartridge head 25 as will be understood from an inspection of Figure 6.

The operating mechanism 16 for the cartridge firing audible signal 13 is carried by the door 10 and includes a mounting plate 34 secured as at 35 to the inner side of the door 10 for the support of arms moyed to operative position from points at opposite sides of the door for engagement with the lever 22 to release the same from the firing pin 20. A 30 lock barrel 36 is rotatable in a bearing opening in the door 10 and houses a bolt that is rotatable therein and operated by the key 37 from the outer side of the door, the inner projecting end 38 of the rotatable bolt being of 35 polygonal formation in cross-section, rotatably extending through the mounting plate 34 and into a similarly formed opening in one end of the arm 39 as shown in Figure 5. The free swinging end of the pivoted arm 50 39 is pivotally mounted upon its upper side by the screw pins 40, one end of a trip lever 41, a bearing block 42 is retained on the mounting plate 34 by the threaded screw pin 43 extending above the lock 42 having a guide 55 for the trip lever 41 by extending through a longitudinal slot 44 formed in said trip lever 41. A guard arm 45 has one end pivotally supported upon the upper end of the screw pin 43 and retained by the head 43a thereof 60 with the free end of the guard arm 45 having depending side flanges 46 between which the forward end of the trip lever 41 extends. A second trip lever 47 is longitudinally slotted at 48 and is received on the screw pin 43 between the block 42 and trip lever 41 as shown 65

in Figure 5, the same extending between the side flanges 46 and the guard arm 45 while its inner end is attached to the pin 49 extending upwardly through the slot 44 in the trip lever 41 and tensioned as at 50 for holding the trip levers 41 and 47 frictionally engaged with each other. 70

With the audible signals 13 or cartridge firing device in the set position shown in Figure 1, with the finger 24 of the lever 22 75 engaged in the side notch 25 of the firing pin 20, the operating mechanism for the signal 13 comprising the trip levers 41 and 47 are set or shifted to positions inwardly of or beneath the forward end of the arm 22 so that 80 when the door 10 is opened, the arm 22 will be moved upon its pivot pin 23 to release the firing pin 20 for firing the cartridge 29, and, as previously stated, the cartridge guard 31 85 shifted to a position aligned with the cartridge to prevent firing thereof. After the door has been locked in the usual manner by the customary lock mechanism 12 from the inner side of the door, the pin 49 that is normally retracted to the inner end of the slot 44 in the trip lever 41 is manually engaged for shifting the trip lever 47 to the full line position shown in Figure 2. When the door is opened, the projecting end of the trip lever 47 engages the lever 22 to release 90 the firing pin. When the trip levers are shifted to set positions from the outer side of the door, the key 37 operates the bolt 38 to swing the arm 39 and move the lever 41 through the dotted line position shown in 95 Figure 4 to the full line position shown in Figure 3, and, assuming that trip levers are being set from the outer side of the door, with the trip lever 47 retracted, the frictional engagement between the two trip levers 100 when both are to be forwardly projected to the operative position shown in Figure 3. It is also possible to manually retract trip levers 41 and 47 from the inner side of the door while engaging the pin 49 to swing the two 105 trip levers upon the pivot guide and screw pin 43 and the arm 39 upon the bolt end 38. 110

A U-shaped frame comprising crenelated side arms 51 shown more clearly in Figure 6 is mounted upon the wall 11 with the free 115 end of the lever 22 extending therebetween. This frame member is a telltale device to indicate to one familiar with the burglar alarm mechanism the fact that the alarm device is in set position. During the initial opening 120 movement of the door, resistance thereto is encountered by endeavoring to force the lever 22 beyond the corrugations of the arms 51 and when repeated resistance is encountered, a person possessed of the proper operating 125 key 37 may then use the same to retract the trip levers 41 and 47 for gaining lawful entry.

A second audible signal, together with a visual signal are associated with the alarm mechanism, and as shown in Figure 1, the 130

battery *a* has lead *b* connected to the firing pin casing 17, while the other lead *c* from the battery *a* extends through the signal 14 comprising a bell 14*a* and from said signal 14, the wire *d* extends to and is connected with the cartridge barrel 27. When the firing pin in the casing 17 moves into engagement with the cartridge 29 in the barrel 27 of the guard arm 31 carried thereby, the circuit is conceived for sounding the bell 14*a*. The visual signal 15 comprising the lamp 15*a* has one wire therefrom as at *e* connected to the firing pin casing 17, the other wire from the lamp 15*a* indicated at *f* extending to a source of energy, in this instance, the source of supply for the house wiring, while the other line *g* having a control switch 8 therein is connected with the cartridge barrel 27, and when the switch 8 is in closed position, the lamp 15*a* is illuminated upon operation of the signal device 13. The lamp 15*a* may be positioned in any particular place desired, while more than one lamp may be included in this circuit.

From the above detailed description of the invention, it is believed that the construction and operation thereof will at once be apparent, and while there is herein shown and described the preferred embodiment of the invention, it is nevertheless to be understood that minor changes may be made therein without departing from the spirit and scope of the invention as claimed.

We claim:

1. Operating mechanism for a burglar alarm comprising devices mounted on a door and separately operable from both sides of the door for placing the operating mechanism in set position, and a control lever operated by said mechanism.

2. Operating mechanism for a burglar alarm comprising devices mounted on a door, and operated at the inner side of the door and key operated at the outer side for placing the operating mechanism in set position, and a control lever operated by said mechanism.

3. Operating mechanism for a burglar alarm comprising devices mounted on a door and separately operable from both sides of the door for placing the operating mechanism in set position, a control lever operated by said mechanism, the devices including a pair of frictionally engaged sliding trip levers, one movable relative to the other.

4. Operating mechanism for a burglar alarm comprising devices mounted on a door and hand operated at the inner side of the door, and key operated at the outer side for placing the operating mechanism in set position, a control lever operated by said mechanism and the devices including a pair of sliding trip levers one movable relative to the other.

5. Operating mechanism for a burglar alarm comprising devices mounted on a door

and separately operable from both sides of the door for placing the operating mechanism in set position, a control lever operated by said mechanism, the devices including a pair of sliding trip levers, one movable relative to the other, and one of said levers being hand operated, and key operated means for moving both levers.

6. Operating mechanism for a burglar alarm comprising devices mounted on a door and hand operated at the inner side of the door, and key operated at the outer side for placing the operating mechanism in set position, a control lever operated by said mechanism, the devices including a pair of sliding trip levers, one movable relative to the other, and one of said levers being hand operated, and key operated means for moving both levers.

7. Operating mechanism for a burglar alarm comprising devices mounted on a door and separately operable from both sides of the door for placing the operating mechanism in set position, a control lever operated by said mechanism, devices including a pair of sliding trip levers, one movable relative to the other, and frictionally engaged with each other, one of said trip levers being hand operated at the inner side of the door, and key operated means engaged with the other lever from the outer side of the door for moving both levers.

8. Operating mechanism for a burglar alarm comprising devices mounted on a door and hand operated at the inner side of the door and key operated at the outer side for placing the operating mechanism in set position, a control lever operated by said mechanism, the devices including a pair of sliding trip levers, one movable relative to the other and frictionally engaged with each other, one of said trip levers being hand operated at the inner side of the door and key operated means engaged with the other lever from the outer side of the door for moving both levers.

9. Operating mechanism for a burglar alarm comprising devices mounted on a door and operable from either side of the door for placing the operating mechanism in set position, a control lever operated by said mechanism, the devices including a pair of sliding trip levers, one movable relative to the other, and frictionally engaged with each other, one of said trip levers being hand operated at the inner side of the door and key operated means engaged with the other lever from the outer side of the door for moving both levers, one of said trip levers being pivotally mounted on a swinging arm that is key operated, a guide pin and said pivoted trip lever being longitudinally slotted with the guide pin extending therethrough, and the other trip lever being slotted and mounted on the guide pin.

10. Operating mechanism for a burglar alarm comprising devices mounted on a door

and hand operated at the inner side of the door and key operated at the outer side for placing the operating mechanism in set position, a control lever operated by said mechanism, the devices including a pair of sliding trip levers, one movable relative to the other and frictionally engaged with each other, one of said trip levers being hand operated at the inner side of the door and key operated means

- 5 engaged with the other lever from the outer side of the door for moving both levers, one of said trip levers being pivotally mounted on a swinging arm that is key operated, a guide pin and said pivoted trip lever being longitudinally slotted with the guide pin extending therethrough, and the other trip lever being slotted and mounted on the guide pin.
- 10 11. Operating mechanism for a burglar alarm comprising devices mounted on a door and operable from either side of the door for placing the operating mechanism in set position, a control lever operated by said mechanism, the devices including a pair of sliding trip levers, one movable relative to the other, and frictionally engaged with each other, one of said trip levers being hand operated at the inner side of the door and key operated means engaged with the other lever from the outer
- 15 20 25 30 35

- side of the door for moving both levers, one of said trip levers being pivotally mounted on a swinging arm that is key operated, a guide pin and said pivoted trip lever being longitudinally slotted with the guide pin extending therethrough, the other trip lever being slotted and mounted on the guide pin, and a guide arm for the operative ends of the trip levers carried by the guide pin.

12. Operating mechanism for a burglar alarm comprising devices mounted on a door and hand operated at the inner side of the door and key operated at the outer side for placing the operating mechanism in set position, a control lever operated by the said mechanism, devices including a pair of sliding trip levers, one movable relative to the other and frictionally engaged with each other, one of said trip levers being hand operated at the inner side of the door and key operated means engaged with the other lever from the outer side of the door for moving both levers, one of said trip levers being pivotally mounted on a swinging arm that is key operated, a guide pin and said pivoted trip lever being longitudinally slotted with the guide pin extending therethrough, the other trip lever being slotted and mounted on the guide pin, and a guide arm for the operative ends of the trip levers carried by the guide pin.

60 In testimony whereof we affix our signatures.
